UNITED STATES PATENT OFFICE.

ALBERT LAUBER, OF NEW YORK, N. Y.

UNIVERSAL PORTABLE SAWING-MACHINE.

No. 825,823.

Specification of Letters Patent.

Patented July 3, 1906.

Application filed December 13, 1905. Serial No. 291,596.

To all whom it may concern:

Be it known that I, ALBERT LAUBER, a citizen of the United States, residing at New York, in the county of New York and State of New York, have invented a new and useful Improvement in Universal Portable Sawing-Machines, of which the following is a specification.

My present invention relates to an improved universal portable sawing-machine, and has for its object to provide a device that is particularly adapted for use in cutting joists after they have been set in a building and to facilitate the cutting of pipe or electric-wire channels, but which may be used for various other purposes incidental to the work of carpenters either in a building during the course of its erection or in a workshop.

Another object of the invention is to provide a machine capable of quick and ready adjustment of the saw-carrying frame to adapt the saw for cutting different depths and for devices for holding the frame in its adjusted position.

Still a further object of the invention is to provide an automatic feed to gradually feed the saw against the work, the said automatic feed being operated by and simultaneously with the operation of the driving-shaft for rotating the saw.

With these briefly-stated objects in view the invention comprises certain details of construction and peculiar combination and arrangement of parts, as will be fully described in the following specification and pointed out in the claims, reference being had to the drawings, in which—

Figure 1 is a perspective view of my machine as used upon joists after the joists have been set in a building, the joists being shown in dotted lines. Fig. 2 is a sectional elevation of the same. In this view the drive-sprocket and driven sprocket are removed, their shafts shown in section, and one of the end brackets of the base being shown in section. Fig. 3 is a detail sectional view drawn on the line 3-3 of Fig. 2, the bracket being shown in a reverse position to that shown in Figs. 1 and 2. Fig. 4 is a detail longitudinal sectional view of the machine. Fig. 5 is a detail perspective view of the sliding frame. Fig. 6 is a detail perspective view of the swinging frame, and Fig. 7 is a detail view of the feeding device, the various parts being detached.

In the drawings, A designates the base of the machine, consisting of the end brackets B

and the tubular rails C. The brackets B are L shape in cross-section and have their ends terminating in split sleeves B', one side of each sleeve having a rib B², which is designed to rest upon the joists when the machine is in position. These sleeves are designed to receive and hold the ends of the rails C, which are firmly clamped within the sleeves by bolts B⁴, operating through ears B⁵, projecting from the sleeve, and extending from the vertical portions of the brackets are central extensions B⁶, each having a threaded sleeve B⁷, in which operates a thumb-screw B⁸, that is designed to engage the side of the joists to clamp the base firmly in position, and when the machine is used upon a bench I provide bolts B⁹, which operate through threaded apertures in the horizontal portions of the brackets, so that the base may be elevated and adjusted to lie perfectly even.

Slidably retained upon the rails is a frame D, consisting of side portions D' D', substantially A-shaped, said side portions being braced and held together by a cross bolt or bar D², which is secured at each end to horizontal members D³ of the side portions. The lower ends of the oblique portions of the frame terminate in tubular sleeves D⁴, through which the rails C pass, and the apexes of the side portions also terminate in tubular sleeves or bearings D⁵, in which is journaled a power-shaft E, that extends slightly beyond each side of its bearings and has fixedly secured upon one end a drive-sprocket F. Mounted upon the extended ends of the power-shaft is a swinging saw-carrying frame G, consisting of the arms G' G', which are connected adjacent their outer ends by a cross bolt or bar G². The inner ends of the arms are formed with sleeves G³, through which the power-shaft passes, and their outer ends with sleeves G⁴, in which is journaled a saw-carrying shaft G⁵, having a saw-blade G⁶, clamped upon one end and a sprocket G⁷ upon its opposite end, the latter having a sprocket-chain G⁸ operating thereon, which also passes around the drive-sprocket F.

Projecting from each side of each arm of the swinging frame are parallel-arranged fingers H, which are curved upon an arc, the radius of which is struck from the center of the power-shaft E. These fingers are designed to straddle clamping thumb-screws I, carried by the sliding frame and projecting from bosses D⁹, formed upon the frame adjacent the sleeves D⁴. The thumb-screws

serve to clamp the swinging frame to the sliding frame after it has been adjusted, so that the saw will cut the desired depth.

- The operation of my machine, so far as described, is as follows: After the base, which in practice is of a length to extend over four joists, has been securely positioned upon the top of the joist the swinging frame is elevated, so that the saw will cut into the joists at the proper depth. The sliding frame is then moved to one end of the rails, and by operating the drive-sprocket (by grasping the grip-handle F' projecting therefrom) the saw may be rapidly revolved, and by moving the sliding frame along the rails the saw is moved into engagement with the other joists to the end of the base, when the joists are rapidly cut. After the joists to the end of the rails have been cut the clamping-screws are unscrewed sufficiently to release the swinging frame, which is then swung over to the opposite side of the sliding frame and adjusted. Then by revolving the saw and moving the frame toward the first joist, or that upon which the bracket rests, it is rapidly cut. It will thus be seen that this operation is exceedingly simple and insures the cut in all the joists being made in perfect alinement, and after one cut has been made in all the joists the saw-shaft is adjusted in its bearings, so that the saw will be in position to cut parallel slots to those first made, when the machine may be removed and adjusted in position upon the other joists in which the grooves or channels are to be made. It is understood that after the parallel cuts have been made in the joists the wood between the cuts is chiseled out to produce the channel.
- In connection with the machine just described I provide an automatic feed for moving the sliding frame along the rails, which is especially desirable when the machine is being operated by an apprentice or inexperienced persons or when working upon old material in which there is likely to be hidden nails or other foreign objects that would injure the saw-blade, and to control the forward movement or the feeding of the saw so that it may be quickly stopped. To meet these requirements, I provide a feed, which is best illustrated in Figs. 4 and 7 of the drawings, and by reference to the figures it will be seen that I provide the power-shaft E with an eccentric-disk J, that is held between one of the tubular sleeves D', and a collar J' carried by the shaft E. The disk J operates in a forked end K' of an oscillating arm K, which is pivotally held upon a sleeve D'', projecting from the horizontal portion of one of the side members of the frame D' and surrounding the cross-bolt D''. Pivotally held to the side of the arm is an inverted-Y-shape lever-arm L, the lower diverging ends of which project upon opposite sides of the cross-bolt D'' and

have pivotally connected to their extreme ends clutch-shoes L' L'', whose lower faces are recessed to snugly fit upon the rails C, but which clear the rails when the lever-arm L is permitted to hang in its normal position. To operate the lever-arm to throw either one of the clutch-shoes into engagement with the rail, I provide a handle-bar M, which is pivotally held upon the same bolts that secure the shoes to the lever-arm. The said handle-bar projects slightly beyond the tubular sleeve D' of the frame D and has its extreme ends bent to provide thumb-handles M'. The central vertical portion of the lever-arm is provided with a series of apertures which register with apertures in the oscillating arm and is pivotally connected to the oscillating arm by means of a bolt L', which may be passed through any one set of registering apertures. It will of course be understood that by changing the pivotal point of the lever-arm a shorter or longer throw or movement of the lower ends of the lever-arm may be had when the oscillating arm is moved by the eccentric. The operation of this feature of my invention is as follows: Assuming the machine has been set in position and the sliding frame is to be moved in the direction indicated by the arrow 1 in Fig. 4 of the drawings, the operator grasps the handle F' of the drive-sprocket with one hand and with the other catches hold of the rail C adjacent the handle-bar and with his thumb presses downwardly and forwardly upon the thumb-piece marked m, which rocks the lower arm and throws the clutch-shoe (marked l) into engagement with the rail. Then by revolving the drive-sprocket F the shaft will be revolved in the direction indicated by the arrow 2, causing the eccentric to move the upper end of the oscillating arm forwardly in the direction indicated by arrow 3, and this movement consequently moves the lever-arm and brake-shoes over in the direction indicated by arrow 4. Now when the eccentric portion of the disk engages the opposite side of the forked member of the oscillating arm its tendency would be to move the upper end of the oscillating arm and lever-arm in the opposite direction to that shown by the arrow 3; but as the shoe l is held tightly against the rail the arm is held against backward movement, and, consequently, the frame is moved forwardly a short distance, the pivotal bolt L', which connects the lever-arm to the oscillating arm acting as the fulcrum-point and the shoe as the fixed point of the lever. This operation is repeated as long as the shaft is revolved and the thumb is held against the handle-bar, but the moment the latter is released the lever-arm will resume its normal position, which will elevate the shoes slightly, thus leaving the frame free to be moved along the rails in either direction, and it may be pointed

ed out that the eccentric operates the feed irrespective of the direction in which the shaft is being revolved, as the operation of the feed is controlled entirely through pressure upon either thumb-pieces of the handle. I have only described the operation of the feed to propel the machine in one direction, as indicated by the arrow 1; but it will of course be understood that should the thumb-piece at the opposite end of the handle be depressed the other clutch-shoe will be forced into engagement with the rail and the machine moved in the opposite direction.

From the foregoing it will be seen that I provide an exceedingly efficient device which may not only be used for facilitating the cutting of joists after they have been set in a building, but may be used to advantage for various other work, such as shopwork or the cutting of flooring when laid in a building, and, in fact, for most any use to which the ordinary saw is put.

Having thus fully described my invention, what I claim as new, and desire to secure by Letters Patent, is—

1. In a machine of the kind described, the combination with a base, of a frame slidably mounted thereon, a frame carried by the first-mentioned frame and adapted for adjustment upon either side of the said first-mentioned frame, and a cutting-tool carried by the second-mentioned frame.

2. In a machine of the kind described, the combination with a base, of a frame slidably mounted thereon, a frame pivotally connected to the sliding frame and adapted to be swung from one side of the sliding frame to the other, means for holding the swinging frame in its adjusted position to the sliding frame, and a cutting-tool carried by the swinging frame.

3. In a machine of the kind described, the combination with a base, of a frame slidably mounted thereon, a shaft journaled in the frame, a second frame journaled upon the shaft and adapted to be swung from one side of the sliding frame to the other, means carried by the sliding frame for holding the swinging frame in position, and a cutting-tool carried by the swinging frame.

4. A machine of the kind described, comprising a base, a frame slidably mounted thereon, a second frame pivotally connected to the first-mentioned frame and adapted for adjustment upon either side of the first-mentioned frame, means for holding the second-mentioned frame in its adjusted position, and a cutting-tool carried by the said second-mentioned frame.

5. A machine of the kind described, comprising a base, a frame slidably mounted thereon, a drive-shaft journaled in the frame and having a sprocket-wheel mounted upon one end, a frame journaled upon the shaft and adapted for adjustment upon

either side of the sliding frame, means for locking the frames together, a shaft journaled in the second-mentioned frame and having a cutting-tool upon one end and a sprocket-wheel upon the opposite end, and a sprocket-chain passing around the said sprocket-wheels.

6. A machine of the kind described, comprising a base consisting of brackets and rails adjustably connected to the brackets, a frame slidably mounted upon the rails, a second frame pivotally connected to the first-mentioned frame and adapted to swing from one side of the first-mentioned frame to the other, means for locking the said frames together, and a cutting-tool carried by the second-mentioned frame.

7. A machine of the kind described, comprising a base consisting of brackets and rails adjustably connected to the brackets, a frame having tubular sleeve portions through which the rails pass and by which the frame is slidably retained thereon, a shaft journaled in the frame, a second frame journaled upon the shaft, a shaft journaled in the second-mentioned frame, a cutting-tool held upon the shaft, a sprocket-wheel journaled upon each of the said shafts and having a sprocket-chain operating thereon, and clamping-bolts carried by the first-mentioned frame and adapted for engagement with the second-mentioned frame, substantially as specified.

8. A machine of the kind described, comprising a base consisting of U-shaped brackets and parallel-arranged rails held in the brackets, a frame having tubular sleeves through which the rails pass, a drive-shaft journaled in the frame, and projecting at each end beyond the frame, said shaft having a drive-sprocket wheel upon one end, a second frame journaled upon the extended ends of the shaft, a shaft journaled in the second-mentioned frame and having a cutting-tool upon one end and a drive-sprocket upon the opposite end, a sprocket-chain passing around the said sprocket-wheels, and means for clamping the second-mentioned frame to the first-mentioned frame.

9. A machine of the kind described, comprising a base consisting of end brackets and parallel-arranged rails adjustably held to the brackets, a frame slidably retained upon the rails, said frame comprising side portions, and a connecting rod or bolt, a shaft journaled in the frame, a frame journaled upon the shaft, said second-mentioned frame comprising parallel-arranged arms and a connecting-bolt, said arms having parallel-arranged fingers extending from each side, a shaft journaled in the arms, and adjustable therethrough, a cutting-tool carried by the shaft, sprocket-wheels held upon the shafts and having a sprocket-chain operating thereon, and clamping-bolts carried by the first-men-

tioned frame and adapted for engagement with the said parallel-arranged fingers of the second-mentioned frame, substantially as specified.

10. A machine of the kind described, comprising a base consisting of end brackets having split sleeves and parallel-arranged rails held in the sleeves, a frame slidably mounted upon the rails, said frame consisting of substantially A-shape side portions, the lower oblique ends of which terminate in sleeves through which the rails pass, the apexes of the side portions also terminating in sleeves, a shaft journaled in the sleeves at the apexes of the side portions, a swinging frame consisting of parallel side arms, one end of each of which is provided with sleeves through which the said shaft passes, and their opposite ends terminating in bearing-sleeves, a shaft adjustably held in the sleeves for the purpose specified, a cutting-disk carried by the shaft, parallel fingers projecting from each side of each arm, clamping-bolts carried by the sliding frame and adapted for engagement with the fingers for the purpose specified, and sprocket-wheels carried by the shafts and having a sprocket-chain operating thereon.

11. A machine of the kind described, comprising a base consisting of end brackets and parallel-arranged rails secured in the brackets, a power-shaft journaled in the frame, a frame journaled upon the shaft and adapted to be swung from one side of the sliding frame to the other, means carried by the sliding-frame for holding the swinging frame in position, a shaft journaled in the swinging frame, a cutting-tool carried by the last-mentioned shaft, sprocket-wheels mounted upon the shafts and having a chain operating thereon, a feeding device carried by the sliding frame and adapted for engagement with the base when thrown into operative position, means for controlling the position of the feeding device, and means for operating the feeding device.

12. A machine of the kind described, comprising a base consisting of end brackets and parallel-arranged rails connected to the brackets, a frame slidably retained upon the rails, a power-shaft journaled in the frame, a swinging frame journaled upon the power-

shaft, and adapted for vertical adjustment, means for holding the swinging frame in its adjusted position, a shaft journaled in the swinging frame, and having a cutting-tool upon one end and sprocket-wheel upon its opposite end, a sprocket-wheel mounted upon the power-shaft, a sprocket-chain operating upon the wheels, an oscillating arm pivotally connected to the sliding frame, one end of which terminates in a forked member, an eccentric-disk carried by the power-shaft and operating in the forked end of the arm, a lever-arm pivoted to the oscillating arm, clutch-shoes carried by the lever-arm, said clutch-shoes being adapted for engagement with one of the rails of the base, and means for throwing either one of the shoes into such engagement.

13. A machine of the kind described, comprising a base consisting of end brackets and parallel-arranged rails, a frame slidably retained upon the rails, a power-shaft journaled upon the shaft and having a sprocket-wheel, a frame journaled upon the shaft, said frame having parallel-arranged fingers projecting therefrom which are designed for engagement by clamping-bolts carried by the sliding frame, a shaft journaled in the second-mentioned frame and having a cutting-tool upon one end and a sprocket-wheel upon its opposite end, a sprocket-chain operating upon the sprocket-wheels, an oscillating arm pivotally connected at one end to the sliding frame, the free end of the oscillating arm being adapted for engagement by an eccentric-disk carried by the power-shaft, an inverted-Y-shaped lever-arm pivotally connected to the oscillating arm, clutch-shoes pivotally connected to the lower ends of the lever-arm and held immediately adjacent one of the rails of the base, and an operating handle-bar connected to the lower ends of the lever-arm, said handle-bar projecting at each end beyond the frame and having its ends terminating in thumb-handles and by which either of the said clutch-shoes is thrown into engagement with the base-rail, substantially as specified.

ALBERT LAUBER.
